*Primary Examiner—B. J. Bullock**Assistant Examiner—Paula Mortimer**Attorney, Agent, or Firm—William M. Hobby, III***[57] CLAIM**

The ornamental design for an equipment case, as shown and described.

DESCRIPTION

FIG. 1 is a top side perspective view of my new equipment case;

FIG. 2 is a rear end elevation;

FIG. 3 is a bottom side elevation;

FIG. 4 is a top side perspective view of the open case; and,

FIG. 5 is a top side perspective view of the open case and screen.

The broken line showing of the wavy lines in FIG. 5 is for illustrative purposes only and forms no part of the claimed design.

FIG. 1FIG. 2FIG. 5FIG. 4FIG. 3
